US00D632736S

(12) **United States Design Patent**
Pascale

(10) **Patent No.:** **US D632,736 S**
(45) **Date of Patent:** **** Feb. 15, 2011**

(54) **ORGANIZER CLIP**

(76) Inventor: **Steven Patrick Pascale**, 1835 Newport Blvd., Suite A-109, Costa Mesa, CA (US) 92627

D152,153 S 12/1948 Harvey
D156,928 S 1/1950 Wooden
2,493,276 A 1/1950 Thruston

(**) Term: **14 Years**

CLAIM

The ornamental design for an organizer clip, as shown and described.

DESCRIPTION

The sole FIGURE is a front view of an organizer clip showing my new design.

The long and short broken lines around the edge of the sole FIGURE define the bounds of the claimed design and form no part thereof.

The evenly spaced broken lines on the sole FIGURE are included to show lines and features on the surface of that form no part of the claimed design.
